UNITED STATES PATENT OFFICE.

ANNIE M. GARDNER AND WILLIAM H. GARDNER, JR., OF SALEM,
MASSACHUSETTS.

DESIGN FOR A PICTURE OR MIRROR FRAME.

SPECIFICATION forming part of Design No. 28,808, dated June 7, 1898.

Application filed January 20, 1898. Serial No. 667,343. Term of patent 7 years.

To all whom it may concern:

Be it known that we, ANNIE M. GARDNER and WILLIAM H. GARDNER, Jr., citizens of the United States, residing at Salem, in the county 5 of Essex and State of Massachusetts, have invented and produced a new and original Design for Picture or Mirror Frames, of which the following is a specification, reference being had to the accompanying drawings, 10 forming a part thereof.

Our present invention relates to a new design for picture and mirror frames.

Figure 1 is a plan view of a frame embodying our new design. Fig. 2 is a cross-section 15 of the same, taken on the line 2 2 of Fig. 1.

Our design consists of a picture or mirror frame A, having upon the face thereof in each upper corner the representation of a female figure, or what is usually termed a "witch," 20 (indicated by the letter B in the drawings,) said figure being shown astride a broom C, and below such representation of the witch is a segmental shield or globè, (indicated by

the letter D.) The faces of the female figures are shown as looking toward each other. 25

The essential feature of the design consists, as stated, in a picture or mirror frame bearing the representation of a female figure, or what is usually termed a "witch," shown astride a broom, said female figures being 30 arranged upon the face of the frame in each upper corner thereof, as illustrated in the drawings.

Having described our invention, what we claim as new, and desire to secure by Letters 35 Patent, is—

The design for a picture or mirror frame as herein shown and described.

In testimony whereof we have hereunto set our hands in presence of two subscribing witnesses. 40
